[57]

ABSTRACT

An inverter circuit for generating a stepped sinusoidal-like output has a transformer with a center tapped primary winding, a source of D.C. voltage connected between the center tap point and ground or other reference point, and a pair of switch means respectively connected between the opposite ends of the primary winding and the common reference point, which switch means are rendered conductive sequentially and during spaced intervals during which an output is desired. Primary winding shunting switch means is connectable across all or half of the primary winding to short circuit that part of the winding carrying current to produce a substantially zero output between each pair of said spaced intervals. The primary winding shunting switch means most advantageously is a transistor or the like whose load terminals are connected between the center tap point of the primary winding and the juncture of a pair of diodes respectively connected to the opposite ends of the primary winding.

STEPPED SINUSOIDAL-LIKE WAVEFORM GENERATING INVERTER CIRCUIT

This invention relates to apparatus for generating relatively low frequency sinusoidal-like signals from a source of direct current, using relatively compact, light-in-weight components, and has its most important application in direct current powered single phase sine-wave power supplies capable of delivering substantial amounts of power for various applications, such as power supplies for satellites and aircraft, where size, weight and/or cost limitations are important considerations.

The generation of low frequency sinewave current of substantial magnitude generally requires extremely bulky equipment, whether it be an electromechanical device, such as motor generator equipment, or electronic circuits. Electronic circuits commonly generate sinewave current from the output of a direct current energized square wave generator or inverter circuit whose output appearing across the output of a transformer is filtered to provide a substantially sinusoidal waveform. A relatively recent development in electronic sinewave generator circuits produce an approximation of a sinewave signal by the superpositioning of a number of square topped pulses of varying width and polarity to provide a stepped waveform whose general outline resembles a sinewave.

U.S. Pat. No. 3,579,081 discloses, as examples of a basic invention also utilized in the present invention, several low frequency sinusoidal sinewave generator circuits each comprising a major and one or more minor bridge circuits each comprising two circuit branches including a pair of current control devices or switches like transistors connected in series circuit relation across a source of D.C. voltage. Each pair of switches in each circuit branch are rendered alternately conductive so only one of these devices is conducting at a time. Different complementary alternating voltage outputs, which suddenly vary between various finite values and zero at different instants of time, are obtained across the output terminals of each of the bridge circuits located at the junctures between the pairs of switches in the circuit branches. The voltage outputs have a finite value about equal to the output of the D.C. voltage source as two non-corresponding pairs of switches of the circuit branches are rendered alternately conductive. In such bridge circuits, the maximum voltage which is applied to each of the switches is the applied D.C. voltage, and load current flows through two switches connected in series across the applied D.C. voltage. These complementary voltage outputs are added together to produce a stepped sinusoidal-like voltage waveform.

The present invention provides stepped sinusoidal-like waveforms preferably utilizing at least a pair of center-tapped transformer inverter circuits which provide different component square topped voltage waveforms which suddenly vary between various finite values and zero at different instants of time and each of which circuits requires three rather than four switches and has load current flowing only through one of the switches at a given time. This has the advantage of eliminating the voltage drop across one switch to increase the efficiency of the circuit as well as reducing the cost and increasing the reliability thereof. However, the use of a center-tapped transformer inverter circuit produces voltage conditions where the main inverter

switches must withstand twice the applied D.C. voltage, and so this circuit has its most advantageous application in lower voltage application than the bridge referred to. In a center-tapped transformer inverter circuit, a pair of main transistor switches or the like are connected across the opposite ends of a center-tapped primary winding of a transformer and a common reference point. A source of D.C. voltage is connected between the center tap of the primary winding and the common reference point. Alternately rendering the transistors conductive over spaced intervals results in the flow of current in opposite directions respectively through the halves of the primary winding to produce voltage pulses of opposite polarity across the secondary winding of the transformer. To obtain a sudden zero output between the desired spaced conducting intervals of the transistors without any build up of undesirably high voltages across the transformer primary winding, a short circuit is directly provided across a winding of the transformer most advantageously across the half of the primary winding conducting current at a given instant of time. In the latter case, a transistor switch or the like is connected between the center tap of the primary winding and the juncture of a pair of diodes respectively connected to the opposite ends of the primary winding so as to complete paths of current flow in the associated halves of the primary winding. Each diode and the load terminals of the latter transistor effectively short circuits the associated half of the primary winding which thereby reflects a short circuit of zero impedance condition across the terminals of the secondary winding. Properly timed control signals are fed to the control electrodes of the various transistors or other switch devices referred to to produce the desired plus, minus or zero output conditions across the transformer secondary winding.

In high power capacity inverter circuits, it is usually desirable to use transformer coupled drive amplifiers. Any feature which reduces the number of transformers in the drive amplifiers will desirably materially reduce the cost, weight and size of an inverter system. With this end in mind, another feature of the invention is the utilization of a common drive transformer for two or more of the inverter switches of the same inverter circuit and/or for the two inverter circuits of the stepped sinusoidal-like waveform generator circuit, even when the switches controlled by the common drive transformer have different conduction patterns. A still further feature of the invention provides more perfect zero output intervals which, in the absence of such feature, is not achieved because of a transformer coupled voltage drop appearing across the primary winding shunting transistor switch and diodes.

The above and other advantages and features of the invention will become apparent upon making reference to the specification to follow, the claims and the drawings wherein:

FIG. 1 is a simplified diagram of a center-tapped transformer inverter circuit designed in accordance with the present invention;

FIG. 2 shows the output from the inverter circuit of FIG. 1;

FIG. 3 shows two center-tapped transformer inverter circuits each providing complementary pulsed output waveforms and connected together to provide a more nearly sinusoidal-like resultant output;

FIG. 4 is an exemplary circuit diagram for the circuit shown in FIG. 3;

FIG. 5 shows various voltages present at various designated points in FIG. 4;

FIG. 6 shows an improvement in the center-tapped transformer inverter circuit shown in FIG. 4 which produces a more perfect zero output condition than that possible with the circuit of FIG. 4;

FIG. 6A shows waveforms present in parts of the circuit of FIG. 6;

FIG. 7 shows a further improvement in the center-tapped transformer inverter circuit of FIG. 4, used for high power applications where greater transistor drive is necessary; and

FIG. 8 is a simplified diagram of a center-tapped transformer inverter circuit constituting a less advantageous form of the invention.

Refer now to FIG. 1 which shows the simplest form of the invention. This inverter circuit, generally indicated by reference numeral 2, includes a transformer 4 having a center-tapped primary winding formed by two primary halves 4a and 4b, and a secondary winding 4c across which an output like E1 shown in FIG. 2 appears. Switches S1 and S2, which may be transistors, are connected respectively between the ends of the primary winding halves 4a and 4b and a common reference point or ground 5. A source of D.C. voltage 6, which may be a battery, is connected between the center-tapped point of the said primary winding and ground. Switch means S3, which may include a control switch like a transistor and diodes to be described, is connected across the primary winding 4a. When the control switch involved is rendered conductive, a short circuit-forming path is formed no matter what the polarities of the voltages or currents in the circuit are at the time involved. This short circuit is then reflected across the secondary winding 4c to provide an effective near zero impedance across the secondary winding to effect a zero voltage output condition for the inverter circuit. A control circuit 7 is provided having a number of different output lines carrying various control signals and respectively connected to switches S1 and S2 and the control switch of switch means S3 to control the conduction and non-conduction thereof. When the switch S1 is rendered conductive for a given interval, current flows through primary winding half 4a and the switch S1 connected in series across the terminals of the D.C. voltage source 6, to induce a flat topped pulse of one polarity across the secondary winding 4c of the transformer 4. Such a pulse lasting for a 120° half cycle centered interval is shown during the first half cycle of the waveform E1 shown in FIG. 2. When the switch S2 is rendered conductive for a given interval, current flows in the opposite direction through the other primary winding half 4b and the switch S2 connected in series across the terminals of the D.C. voltage source 6, to induce a flat topped pulse of opposite polarity across the secondary winding 4c of the transformer 4. Such a pulse of opposite polarity lasting for a 120° interval centered in the second half cycle is shown by the negative going portion of the waveform E1 in FIG. 2. To quickly terminate the flow of current in the primary winding to effect a zero output condition interval (like the 60° zero output interval between the positive and negative pulses of the waveform E1 shown in FIG. 2), the control switch portion of switch means S3 is rendered conductive for the interval involved.

To provide a stepped sinusoidal-like voltage waveform, one or more other pulse waveforms can be added to the waveform E1 shown in FIG. 2 as, for example, the waveform E2 shown in FIG. 5, which for each half cycle of waveform E1 supplies additive pulses during the first and last 30° interval and during the middle 60° interval of each half cycle. These pulses have an amplitude approximately one-third that of the amplitude of the waveform E1. (Other more complex waveforms may be added, such as those shown in said U.S. Pat. No. 3,579,081). Waveform E_o in FIG. 5 represents the summation of the waveforms E1 and E2. In the present invention, to provide a waveform like E2, a second center-tapped transformer inverter circuit 2' is provided in addition to the inverter circuit 2, as shown in FIG. 3. (The inverter circuits 2 and 2' will sometimes be referred to as the major and minor inverter circuits). The inverter circuit 2' shown in FIG. 3 is substantially identical to the inverter circuit 2 (and corresponding parts thereof have been similarly identified in FIG. 3 except for the addition of a prime (') to the reference characters) except that the turns ratio of the primary and secondary windings of the transformers 4 and 4' and the control signal waveforms produced by control circuits 7 and 7' are different. The secondary windings 4c and 4c' are connected in series across output terminals 8 and 10 at which the output waveform E_o in FIG. 5 appears.

Refer now to the circuit diagram shown in FIG. 4, which shows a transistorized embodiment of the invention where certain portions of the control circuitry 7 and 7' used to control the primary winding short circuiting switch means S3 and S3' are combined into a common control circuit. As thereshown, the various transistor switches S1, S2, S1' and S2' are NPN type transistors with the collectors 12c of the transistor switches S1 and S2 and the collectors 12c' of the transistor switches S1' and S2' respectively connected to the outer ends of the associated primary winding halves 4a-4b and 4a'-4b'. To provide a path for current flow for out-of-phase current components where reactive loads are utilized, reverse current conducting diodes 20-22 and 20'-22' are respectively connected across the emitter and collector pairs of the transistor switches S1-S2 and S1'-S2'.

The primary winding bypassing transistor control switches of switch means S3 and S3' as illustrated are PNP type transistors 14 and 14' having their emitters 14e-14e' connected to the center-tap points of the associated primary windings of the transformers 4 and 4'. The collectors 14c-14c' of the transistors 14-14' are respectively connected to the juncture points of pairs of diodes 16-18 and 16'-18'. The anodes of the diode pairs 16-18 and 16'-18' are respectively connected to the collectors 14c-14c' of the transistors 14-14', and the cathodes thereof are respectively connected to the outer ends of the primary windings of the associated transformers 4 and 4'. When current is flowing through the primary winding half 4a or 4a', the conduction of the transistors 14 or 14' will establish a current path for the current flowing in the associated winding half 4a or 4a', and to effectively short circuit the associated transformer secondary winding 4c and prevent the build-up of high voltages when the associated transistor switch S1 or S2 is rendered non-conductive. This current path includes the emitter and collector of the transistor 14 or 14' and the diode 16 or 16'. Similarly, when current

is flowing in the primary winding half $4b$ or $4b'$, the conduction of transistor 14 or $14'$ establishes a short current forming path across the associated primary winding half $4b$ or $4b'$ and including the emitter and collector of the transistor 14 or $14'$ and the associated diode 18 or $18'$. In FIG. 4, a common source of D.C. voltage 6 is utilized for both major and minor inverter circuits 2 and $2'$. Accordingly, the positive terminal of the D.C. voltage source 6 is connected to the center-tap points of the primary windings of the transformers 4 and $4'$ and the negative terminal thereof is grounded.

The bases $12b$ of the transistor switches $S1$ and $S2$ of the major inverter circuit 2 are respectively connected to outputs $24a$ and $24b$ of a major circuit turn-on drive means 24 at which outputs the control signal waveforms $3a$ and $3b$ shown in FIG. 5 appear. Each of these waveforms provides a positive output during the intervals at which the associated transistors are to be rendered conductive which, in the example of the invention being described, is a centered 120° interval for one half cycle of each cycle of operation of the inverter circuit. Similarly, the bases $12b'$ of the transistor switches $S1'$ and $S2'$ of the minor inverter circuit $2'$ are respectively connected to control signal outputs $24a'$ and $24b'$ at which the control signals Ea' and Eb' shown in FIG. 5 appear. Each of the waveforms Ea' and Eb' provide a 30° positive pulse for the first and last 30° intervals and a centered 60° positive pulse of the half cycle during which the associated transistor switch is to be rendered conductive. Such pulses will render the associated NPN transistors conductive during the period such positive pulses exist.

For high power inverters, a simple drive circuit for the primary winding bypassing transistor switches 14 and $14'$ would probably not suffice. Accordingly, the circuit of FIG. 4, which is assumed to be one requiring a relatively high power drive to the transistors $14-14'$ includes a unique control circuit which utilizes only one main drive transformer for both the major and minor inverter circuits. To avoid transformer core saturation, it is important that, over a cycle of operation of the transformer involved, approximately the same amount of positive and negative ampere turns of flux generating power are produced within the transformer core. It should be observed that the zero output intervals of the output waveforms $E1$ and $E2$ of the major and minor inverter circuits, during which the primary winding bypassing transistors $14-14'$ are to be respectively conductive, occur at different intervals of time, and over a cycle of operation of the inverter circuit occupy the same total periods, namely 240° (120° each half cycle). This fact is taken advantage of in the design of the drive circuit.

Accordingly, the turn-off drive circuit includes a drive transformer 26 with a center-tapped primary winding having primary windings halves $26a-26b$, the juncture of which is connected to one of the terminals of a source of D.C. voltage, a positive terminal in the exemplary circuit being described, which may be the positive terminal of the D.C. voltage source 6 . Transformer 26 has a center-tapped secondary winding with secondary winding halves $26c-26d$. The center-tap point of the secondary winding is connected to the positive terminal of the D.C. voltage source 6 to which the emitter $14e-14e'$ of the transistors $14-14'$ are also connected. The outer ends of the secondary winding halves $26c-26d$ are respectively connected by conductors

$27-27'$ to the bases $14b-14b'$ of the PNP transistors $14-14'$ which require a negative voltage to render them conductive. The voltage appearing between the outer terminal of the secondary wind half $26c$ and the positive center tap point thereof control the conduction of the transistor 14 , and the voltage appearing between the outer terminal of the secondary winding half $26d$ and the positive center tap point thereof controls the conduction of the transistor $14'$.

10 The outer terminals of the primary winding halves $26a-26b$ are respectively connected to the collectors $18c-30c$ of a pair of NPN transistors $28-30$ forming part of an inverter circuit. The emitters $28e-30e$ of the transistors $28-30$ are shown connected to a common ground point, and the bases $28b-30b$ thereof respectively are shown connected to the output terminals $32a-34a$ of major and minor circuit turn-off drive means which generate the control signal waveforms $Ec-Ec'$ shown in FIG. 5, which respectively render NPN transistor switches $28-30$ conductive during the positive "1" amplitude intervals of the waveforms $Ec-Ec'$. It will be noted that the control signals $Ec-Ec'$ fed to the bases $28b-30b$ have their positive "1" amplitude levels at different instants of time and, over a full cycle, the sum of the "1" amplitude intervals thereof, is the same for the two waveforms. Since conduction of transistor switches $28-30$ effects current flow respectively in opposite directions through primary winding halves $26a-26b$, the plus and minus ampere turns generated in the transformer 26 over an operating cycle are equal, providing a balanced operation of the transformer.

When transistor 28 is conductive and current flows 35 through the upper primary winding half $26a$ of the transformer 26 , the outer or upper terminal of the secondary winding half $26c$ viewed in FIG. 4 will be negative with respect to the positive center tap point thereof and the outer or bottom terminal of the secondary 40 winding half $26d$ will be positive with respect to the positive center tap point thereof. Since these terminals are respectively connected by the conductors $27-27'$ to the bases of PNP transistors $14-14'$ where a negative voltage effects conduction and a zero or positive voltage effect non-conduction thereof, it is apparent that 45 the intervals during which transistor switch 28 is conductive will only have an effect upon the transistor 14 of the major inverter circuit 2 . Similarly, when the transistor 30 is rendered conductive and current flows 50 through the bottom primary winding half, the bottom or outer terminal of the secondary winding half $26b$ will be negative with respect to the positive center tap point thereof and the outer or upper terminal of the secondary winding half $26c$ will be positive with respect to the center tap point thereof. Conduction of the transistor 30 will, therefore, only result in the conduction of the transistor $14'$ of the minor inverter circuit $2'$.

In order to effectively terminate all current flow in 60 the transformer 26 during those intervals when the transistor switches $28-30$ are both to be in a non-conductive state, an additional secondary winding, which is illustrated as center-tapped winding having secondary winding halves $26e-26f$, is provided on the transformer 26 , so that one or the other of these winding halves can be short circuited. This has the same effect as short circuiting the primary winding. The juncture points of the secondary winding halves $26e-26f$ is 65 grounded, and the outer terminals thereof are respec-

tively coupled through similarly connected diodes 38-40 to a common point, in turn, connected to the collector 36c of an NPN transistor switch 36. The emitter 36e of the transistor switch 36 is grounded and the base 36b thereof is connected to the output 42a of a turn-off aiding means 42, which is a circuit generating the waveform Ed in FIG. 5 which comprises 60° positive pulses occurring during the intervals when the transistor switches 28-30 are both non-conductive. When such positive pulses are fed to the NPN transistor switch 36, the same becomes conductive to effectively short circuit that secondary winding half 26e or 26f across which a voltage is induced of a polarity which effects conduction of the associated diode 38 or 40.

Refer now to FIG. 6 which show a further improvement in the inverter circuits 2 - 2' shown in FIG. 4. When current flows through either of the primary winding bypassing transistors 14 or 14' and the associated diodes 16-18 or 16'-18', the voltage drop occurring across these elements acts as a low voltage source of, for example, the order of magnitude of 1 1/2 volts. This voltage source is stepped up by the inductive coupling between the associated primary winding half 4a-4a' or 4b-4b', and appears as an undesired voltage, for example, three or four times this amount across the associated secondary winding 4c or 4c'. In the preferred form of the invention, this voltage is substantially eliminated by circuitry like that shown in FIG. 6 which includes the addition of a low power transformer 44 having a primary winding 44a and secondary winding 44b - 44b'. One of the corresponding terminals of primary winding 44a is shown grounded and the other terminal thereof is connected to the output 48a of a circuit turnoff drive means 48 which is a circuit which generates, for example, the waveform Ee shown in FIG. 6A when the inverter circuit involved is the major inverter circuit 2, and the waveform Ee' shown therein when the inverter circuit involved is the minor inverter circuit 2'. As shown in FIGS. 6A, the waveforms Ee and Ee' comprises pulses alternating between a positive "1" and a negative "1" amplitude level during intervals which the primary circuit shorting transistors 14-14' are conductive. One of the corresponding ends of the secondary windings 44b-44b' (the upper ends as illustrated) of the transformer 44 are respectively connected to the cathode of the diode 16 or 16' and the outer or bottom end of the primary winding half 4b or 4b' of the transformer 4 or 4'. The bottom ends of the secondary windings 44b-44b' are respectively connected to the outer or upper end of the primary winding half 4a or 4a' of the transformer 4 or 4' and the cathode of diode 18 or 18'. The anodes of the diodes 16-18 or 16'-18' are respectively connected to the collector 14c-14c' of the transistor 14 or 14'. The cathodes of the latter diodes, instead of being connected to the outer ends of the primary winding halves 4a-4b or 4a'-4b' of the transformers 4 or 4' as in the case of the circuit of FIG. 4, are instead connected to the non-corresponding ends of the secondary windings 44b - 44b'. Accordingly, when the voltage at the end of the secondary winding 44b connected to the cathode of the associated diode 16 or 16' is negative with respect to the opposite end thereof, the end of the secondary winding 44b' connected to the cathode of diode 18 or 18' will be positive with respect to the opposite end thereof, and visa versa. Thus, each half cycle, the polarity of the voltages induced into the secondary windings

44b-44b' alternate from that present during the previous half cycle.

The phase of the voltage waveforms Ee and Ee' applied to the primary winding 44a-44b' of the transformer 44 is such that the polarity of the voltages induced across the secondary windings 44b-44b' cancel the voltage drop occurring across the conducting transistor 14 or 14' and the then conducting diode 16 or 16', or 18 or 18'. The amplitude of the voltages induced in the secondary windings 44b-44b' is such as substantially to cancel out the voltage drops developed across the transistor 14 or 14' and the diodes 16-18 or 16'-18', so that there will be little or no resultant voltage coupled into the secondary windings 4c or 4c'. (The polarities shown in FIG. 6 of the voltages involved correspond to the polarities of the voltages present during the conducting intervals of the diodes and transistor switches involved, which occur during different half cycles).

For especially high power inverter systems, such as for inverters above a kilovolt ampere of capacity, it is desirable also to utilize drive circuits for the main transistor switches S1-S2 and S1'-S2' of the major and minor inverter circuits 2 and 2' like that shown in FIG. 7. Such drive circuits are similar to the drive circuits shown in FIG. 4 for driving the primary circuit bypassing transistors 14-14'. Accordingly, a transformer 50 is provided having a center-tapped primary winding constituted by primary winding halves 50a-50b to the juncture point of which is connected the positive terminal of a source of D.C. voltage, like the D.C. voltage source 6, and a center-tapped secondary winding having secondary winding halves 50c-50d, the juncture point of which is grounded. The opposite ends of the secondary winding halves 50c-50d are respectively connected to the bases of the associated pairs of main transistor switches S1-S2 or S1'-S2'. A pair of NPN transistor switches 52-54 are provided having collectors 52c-54c connected to the opposite ends of the primary winding halves 50a-50b, and grounded emitters. The bases 52b-54b of the transistor switches 52-54 respectively are connected to the output terminals 56a-56b of turn-on drive means 56, which terminals respectively have the control voltage waveforms Ea-Eb' or Ea'-Eb' shown in FIG. 5 applied thereto to effect the desired conduction of the transistor switches 52-54. To terminate conduction in the transformer windings during the intervals the transistor switches 52-54 are not to be conducting, a secondary winding comprising secondary winding halves 50e-50f is provided on the transformer 50, the juncture point of which is grounded and whose opposite ends are respectively connected through diodes 60-62 to the collector 58c of a NPN transistor 58 whose emitter is grounded and whose base is connected to the output terminal 64a of a turn-off drive means 64 which produces a control voltage waveform having a positive "1" amplitude level during those intervals when the transistors 52-54 are both non-conductive, namely during the "1" amplitude intervals of the waveforms Ec or Ec' shown in FIG. 5.

It should be understood that filter circuits (not shown) would be connected to the output of the various generator circuits above described to provide a substantially ripple-free sinusoidal-like waveform.

The various specific forms of the present invention above described provide very effective, efficient, single phase stepped sinusoidal-like waveform generator cir-

cuits of minimum complexity, weight and size for appreciable power handling capacities. Three such single phase circuit properly phased could provide a three phase system, where desired.

It should be understood that numerous modifications may be made in the most preferred forms of the invention described without deviating from the broader aspects thereof. For example, while an important specific aspect of the invention is the location of the short circuit producing switch means 3 as described across the primary windings of the transformer where in the battery operated systems, voltages of lower magnitude are present thereby requiring lower voltages and less expensive transistors, in accordance with the broader aspects of the invention, the switch means for effecting an effective short circuit across the secondary winding 4c of the output transformer 4 may be located across the secondary winding 4c as illustrated in FIG. 8. As there shown, a PNP transistor 14" is shown with its emitter 14e" connected to the juncture of the cathodes of diodes 16a-18a whose anodes are respectively connected across the upper and lower ends of the secondary winding 4c, and its collector 14c" is connected to the juncture of the anodes of diodes 18b-16b whose anodes are respectively connected across the upper and lower ends of the secondary winding 4c. The base 14b" of the transistor 14" is connected to the output of the control circuit 7 which provides pulses during those intervals when it is desired to produce a zero output for the inverter circuit. It is thus apparent that when the upper end of the secondary winding 4c is positive with respect to the bottom end thereof, a short circuit path is established extending through the diode 16a, the emitter and collector of transistor 14 and the diode 16. When the upper end of the secondary winding 4c is negative with respect to the bottom end thereof, a short circuit path is established extending through diode 18a, the emitter to collector of transistor 14" and the diode 18b.

I claim:

1. A stepped alternating voltage generating circuit comprising: a transformer having a center tapped primary winding and at least one secondary winding; a source of D.C. voltage having a pair of D.C. output terminals, said D.C. output terminals being connected between a center tap point on said primary winding and a reference point; first and second switch means respectively connected between the ends of said primary winding and said reference point; control means for alternately rendering said switch means conductive during spaced intervals to effect current flow sequentially in opposite directions through different halves of said primary winding to generate pulses alternating in polarity in said secondary winding spaced by intervals where the output is substantially zero; and means for ensuring the sudden and continued disappearance in the output across said secondary winding during said spaced intervals including third switch means connectable across a winding of said transformer, and control means for rendering the latter switch means conductive during said spaced intervals wherein said third switch means is a current control device having a pair of load terminals connected in series with the center tap point of said primary winding, and there is associated with said third switch means a pair of rectifier means connected respectively in the same sense between the load terminal of said current control device remote from said primary

winding and the opposite ends of said primary winding, to form respective paths shunting the respective halves of the primary winding to bypass the current flow therethrough.

5 2. A stepped alternating voltage generating circuit comprising: a major and a minor inverter circuit, each inverter circuit comprising a transformer having a primary winding and at least one secondary winding, a pair of D.C. voltage input terminals connected between 10 a center tap point on said primary winding and a reference point, first and second switch means respectively connected between the ends of said primary winding and said reference point, first control means for alternately rendering said first and second switch means conductive during spaced intervals to effect current flow sequentially in opposite directions through different halves of said primary winding to generate pulses 15 alternating in polarity in said secondary winding spaced by intervals where the output is substantially zero, and means for ensuring the sudden and continued disappearance in the output across said secondary winding during said spaced intervals comprising third switch means connectable across a winding of said transformer and second control means for rendering the latter switch means conductive during said spaced intervals; the control means of said major and minor bridge circuits rendering the associated first, second and third switch means conductive in different but complementary conduction patterns so the summation of the outputs of the secondary windings of the associated transformers produces a stepped, sinusoidal-like waveform; and means connecting the secondary windings of the transformers of said major and minor bridge circuits in series voltage additive relation.

3. The circuit of claim 2 wherein said third switch means of each inverter circuit is a current control device having a pair of load terminals connected in series with the center tap point of said primary winding and 40 a control terminal which effects conduction of the switch means when a drive signal of a given polarity is fed thereto by said second control means, and there is associated with each third switch means a pair of rectifier devices respectively coupled in the same sense between the load terminal of said current control device remote from said primary winding and the opposite ends of said primary winding, to form respective paths shunting the respective halves of the primary winding to bypass the current flowing therethrough.

45 4. The circuit of claim 2 where the conduction pattern of the first, second and third switch means of said major inverter circuit is that said first and second switch means are identically alternately rendered conductive during successive half cycles, each such switch means having one conducting interval occupying a majority of and centered in the half cycle involved, leaving relatively narrow non-conducting intervals at the beginning and end of the half cycle, and the third switch means is conductive during the intervals when said first and second switch means are not conductive; the conduction pattern of the first, second and third switch means of said minor inverter circuit is that said first and second switch means are identically alternately rendered conductive during successive half cycles, each such switch means having during each half cycle when the same is conductive a half cycle centered conducting interval and conducting intervals corresponding to

said narrow non-conducting intervals of the corresponding switch means of the major inverter circuit.

5. The circuit of claim 3 wherein the conduction pattern of the first, second and third switch means of said major inverter circuit is that said first and second switch means are identically alternately rendered conductive during successive half cycles, each such switch means having only one conducting interval occupying a majority of and centered in the half cycle involved, leaving relatively narrow non-conducting intervals at the beginning and end of the half cycle, and the third switch means is conductive during the intervals when said first and second switch means are not conductive; the conduction pattern of the first, second and third switch means of said minor inverter circuit is that said first and second switch means are identically alternately rendered conductive during successive half cycles, each such switch means having during each half cycle when the same is conductive only a half cycle centered conducting interval and conducting intervals corresponding to said narrow non-conducting intervals of the corresponding switch means of the major inverter circuit; the sum of the non-conducting intervals of the first and second switch means of the major inverter circuit over each cycle thereof being substantially the same as the sum of the non-conducting intervals of the first and second switch means of the minor inverter circuit; and said second control means of the said major and minor inverter circuits being a common inverter drive circuit comprising a transformer having a center-tapped primary winding and at least one secondary winding, a source of D.C. voltage having a pair of D.C. output terminals, said D.C. output terminals being connected between a center tap point on said primary winding and a reference point, first and second switch means respectively connected between the ends of said primary winding and said reference point, the latter secondary winding having a center tap point coupled to said reference point of said major and minor inverter circuits and the opposite ends thereof being respectively connected to said control terminals of said third switch means of said major and minor inverter circuits, major inverter circuit turn-off drive means and minor inverter circuit turn-off drive means for respectively rendering said first and second switch means of the common drive inverter circuit conductive over intervals corresponding to the desired conducting intervals of said third switch means to said major and minor inverter circuits.

6. An inverter circuit for cyclically driving two separate current control devices conductive in a conduction sequence wherein one of the current control devices is to be rendered conductive at a different time and more frequently than the other of same over a given cycle, each of said current control devices having load terminals and a control terminal which effects the conduction through the load terminals when voltage of the same given polarity is applied thereto, said inverter circuit comprising: a transformer having a center tapped primary winding and at least one center tapped secondary winding, a pair of D.C. input terminals connected between the center tap point on said primary winding and a common reference point, first and second switch means respectively connected between the ends of said primary winding and said reference point, means connecting the opposite ends of said center tapped secondary winding respectively to the control terminals of said

pair of current control devices, and first and second control means for respectively controlling the conduction of said first and second switch means in accordance with the desired conduction patterns of said first and second current control devices, said first and second control means effecting cyclic conduction patterns of said first and second switch means wherein a summation of the conducting intervals of each of said first and second switch over a given cycle of operation is identical to provide balanced operation of the transformer.

7. The inverter circuit of claim 6 wherein said first and second current control devices and said first and second switch means are to be rendered conductive during spaced conducting intervals requiring cessation of current flow in said center tapped primary winding of the inverter circuit over prolonged intervals of time, and there is provided a second center tapped secondary winding on said transformer whose center tap point is connected to said common reference point and whose opposite ends thereof are coupled to a pair of rectifier means connected in the same sense to a common point, third switch means connected between said common point and said common reference point, and control means for said third switch means for rendering the same conductive during those intervals when current flow is to cease in said center tapped primary winding, conduction of said third switch means and one of said rectifier means establishing a low impedance short-circuiting path across one of the halves of said center tapped secondary winding.

8. An inverter circuit comprising: a transformer having a center tapped primary winding and at least one secondary winding, a pair of D.C. input terminals connected between the center tapped primary winding and a reference point, first and second means respectively connected between the ends of said primary winding and said reference point, control means for rendering said first and second switch means conductive respectively over spaced intervals of time wherein only one or the other of said switch means is conductive over any given interval and that interval is spaced from an interval during which the other switch means is to be rendered conductive, the conduction of said first and second switch means respectively resulting in current flow in opposite direction in different halves of the center tapped primary winding, means for terminating current flow through said primary winding between the spaced intervals during which the first and second switch means are conductive comprising a center tapped secondary winding of said transformer having a center tap point connected to said reference point and a pair of rectifier means connected in the same sense to a common point, and third switch means connected between said common point and said reference point, and control means for rendering said third switch means conductive when termination in the current flow through both halves of said primary winding is desired, to establish a short circuit path through said third switch means and one of said rectifier means across one of the halves of said center tapped secondary winding.

9. A stepped alternating voltage generating circuit comprising: a transformer having a center-tapped primary winding and at least one secondary winding, a pair of D.C. input terminals connected between a center tap point on said primary winding and a reference point, first and second switch means respectively connected between the ends of said primary winding and

said reference point, control means for alternately rendering said first and second switch means conductive to effect current flow sequentially in opposite directions through different halves of said primary winding, to generate pulses alternating in polarity in said secondary winding and spaced by intervals where the output is substantially zero, and turn-off means for ensuring the sudden and continued disappearance in the output across said secondary winding during said spaced intervals including third switch means connectable across at least the half of said primary winding carrying current at any instant, control means for rendering the latter switch means conductive during said spaced intervals, the conduction of said latter switch means resulting in a voltage drop thereacross which when applied across the primary winding will effect an imperfect zero output across said secondary winding, and zero output aiding means including means for applying a voltage in series with said switch means and said primary winding which substantially cancels the voltage otherwise applied across said primary winding halves during the period a zero output is desired.

10. The circuit of claim 9 wherein said third switch means is a current control device having a pair of load terminals connected in series with a center tap point of said primary winding and there is associated with said third switch means a pair of rectifier means respectively coupled in the same sense to the load terminal of said current control device remote from said primary winding; and said zero output aiding means comprises second transformer means having a primary winding and a pair of secondary windings respectively connected in an opposite sense between the opposite ends of said center tapped primary winding of the first mentioned transformer and said pair of rectifier means, and a source of alternating voltage connected to said primary winding of said second transformer means to pro-

duce in said respective secondary windings thereat voltages of a polarity which respectively cancel out the voltage drop across the associated rectifier means and said third switch means during the half cycle when the associated rectifier means is operative to shunt the associated primary winding half.

11. A stepped alternating voltage generating circuit comprising: a transformer having a center-tapped primary winding and at least one secondary winding, a pair of D.C. input terminals connected between a center tap point on said primary winding and a reference point, first and second switch means respectively connected between the ends of said primary winding and said reference point, control means for alternately rendering said first and second switch means conductive to effect current flow sequentially in opposite directions through different halves of said primary winding to generate pulses alternating in polarity in said secondary winding and spaced by intervals where the output is substantially zero, and turn-off means for ensuring the sudden and continued disappearance in the output across said secondary winding during said spaced intervals including third switch means having a pair of load terminals connected in series with the center tap point of said primary winding, and a pair of rectifier means respectively coupled in the same sense to the load terminal of said third switch means remote from said primary winding, and means comprising second transformer means having a primary winding and a pair of secondary windings respectively connected in an opposite sense between the opposite ends of said center tapped primary winding of the first mentioned transformer and said pair of rectifier means, and a source of alternating voltage connected to said primary winding of said second transformer.
